TOY ANIMAL, AUTOMOBILE, AND THE LIKE
PROPELLED BY THE RIDER

Harry Sebel, London N. 3, England

Application April 2, 1942, Serial No. 437,316
In Great Britain February 28, 1942

11 Claims. (Cl. 280—1.17)

The present invention relates to wheeled toys and amusement devices of the type which are propelled by the rider.

An object of the invention is to provide a wheeled toy for children which is propelled by muscular movement of both the body and legs of the rider and thus to provide a beneficial exercise for children.

Another object of the invention is to provide an amusement device suitable for exercise by adults and which may be employed as an amusement device in fairground apparatus and for similar purposes.

A further object of the invention is to provide a wheeled toy or amusement device which simulates the action of a horse or other animal there being movement of both the front and back legs by an up and down movement of the body of the rider and the flexing of the rider's legs.

A further object of the invention is to provide a wheeled apparatus of the type referred to which includes front and back legs mounted on wheels adapted to rotate only in a forward direction and pivot points for the front pair of legs and the rear pair of legs and flexible connection means between these pivot points adapted to support the body and the legs of the rider to produce on movement of the body and legs of the rider a pivotal action of the legs about the pivot points alternately towards and away from one another to produce a forward motion of the apparatus.

Preferably two or more flexible connections are provided between the front and back legs and may be constituted by spring elements or pivoted links and it is preferred when there are two flexible connections for at least one of these connections to constitute a spring element which serves to hold the toy erect.

The invention will now be described with reference to the accompanying drawings in which:

Figure 1 shows a perspective view of a toy according to the present invention;

Figure 2 and Figure 3 show the action of this construction;

Figure 4 shows a modification of the spring mounting of the toy shown in Figure 1;

Figures 5 and 6 show diagrammatically the action of the toy as shown in Figure 4;

Figure 7 shows a perspective view of another construction according to the invention;

Figures 8 and 9 show the action of the toy as shown in Figure 7; and

Figures 10 and 11 show details of the construction of Figure 7;

Figure 12 shows a further construction according to the invention, and

Figures 13 and 14 illustrate the action of the toy, as shown in Figure 12.

Fig. 15 shows to an enlarged scale an arrangement for limiting rotation of the wheels to one direction.

Referring to Figure 1 a toy horse comprises a pair of front legs 1 and a pair of rear legs 2 carried on wheels 3 which are provided with a simple pawl and ratchet 37, 38 (Fig. 15) so as to prevent their rotation in a backward direction. The front legs 1 are provided with a vertical spindle 4 which passes through a tubular bushing 5. This tubular bushing has secured to it, conveniently by welding, the front end of a semi-elliptic spring 6. The attachment of this spring to the bushing 5 is reinforced by a short spring 7 to form a triangular mounting. The rear end of the spring 6 is welded to the top of the rear legs 2 and a saddle 8 is supported on the spring 6 at or near the apex of the spring.

Also connecting the rear legs to the front portion of the apparatus is a second elliptic spring 9 which is pivoted on a bracket 10 below the point of attachment of the spring 6 to the rear legs 2 and is pivoted at its front end in a bracket 11 depending from the front end of the spring 6. Stirrups 12 are secured to the spring 9 either at its lowest portion or at some point mid-way between its centre and front ends.

The spindle 4 carries a T-head 13 for steering purposes, the spindle 4 being rotatable within the bushing 5. The whole apparatus may, if desired, be covered with suitable material to simulate a horse and a horse's head may be attached to the spindle 4 as shown in chain line in the drawings.

The action of the toy is shown in Figures 2 and 3. On the weight of the rider being placed on the stirrups 12 as shown by the arrow in Figure 2 the legs 1 and 2 are drawn together to the position shown. Because of the pawl and ratchet of the wheels 3 the front legs remain in the same position and the rear legs are drawn forward. On transference of the weight of the rider to the saddle 8 in the direction of the arrow shown in Figure 3 the legs 1 and 2 are spread as shown. Again, in view of the pawl and ratchet wheels 50 the rear wheels cannot move in a rearward direction and so the whole movement is taken on the front legs which move forward a proportionate distance. In this manner by alternately applying the rider's weight to the stirrups and saddle the toy advances in a series of bounds.

The apparatus shown in Figure 4 operates on similar lines only in this case instead of two opposed semi-elliptic springs there is employed a U-spring 15 the two ends of which are pivoted to the tubular bushing 5 and the rear legs 2 are secured to the base of the spring 15. Reference to Figures 5 and 6 will show that the action of the toy is similar to that shown in Figure 1, weight on the stirrups serving to close the front and back legs together and weight on the saddle serving to spread the legs apart. This construction is a simpler one for assembly the rear legs 2 merely being welded to the base of the U-spring 15 and the two ends of the spring having eyes which are supported by pins carried in suitable shackles on the tubular bushing 5.

Figure 7 shows a different construction of toy which, however, has exactly the opposite action to those previously described with reference to Figures 1 to 6. In this case the saddle 8 is supported on a semi-elliptic spring as in the previous embodiments, but instead of the stirrups being supported by an opposed semi-elliptic spring this spring is replaced by a knuckle joint consisting of two arms 16 and 17 which are fixedly secured to the front and rear legs and which are pivoted together at their inner ends at 18.

To limit the angular movement between the arms 16 and 17 each of these arms are extended beyond the pivot point 18 and carry L-shaped cleats 19 close to and on the opposite sides of the pivot point 18, which cleats act as stop members for the extensions of the arms and so limit the angular movement of the arm members 16 and 17, in both directions.

Figure 10 shows details of the manner in which the saddle spring 6 is secured to the rear legs by means of a welded bracket 20 which also serves as a cross-member uniting the rear legs 2. The arm 16 is also welded to a similar cross-bracket 21 although in this case, of course, the arm is not pivoted as is the spring 6 but is rigidly secured. The front end of the spring 6 and the front end of the arm 17 are similarly secured to a U-bracket 22 which is hinged by means of a pin 23 to support brackets 24 and 25 which also serve as cross-members uniting the front legs 1. A handle 26 is pivotally secured to the upper bracket 25 to serve as a steering handle, the front legs, of course, being rotatable about the pin 23. The action of the toy is shown in Figures 8 and 9 and is opposite in operation to the constructions shown in Figures 1 to 6. The stirrup in this case is not placed below the saddle 8 but is situated approximately mid-way between the pivot point 18 and the front legs, and comprises an adjustable stirrup in which a V-shaped stirrup member 27 is provided at the bottom of the V with a cross-bracket to form a triangular aperture. This stirrup member 27 fits over a strut member 28 of T-section the base of which is provided with a plurality of notches 29 into one of which the base of the V of the stirrup member 27 is placed and is kept in position by the cross bracket bearing on the head of the T.

Figure 12 shows a construction on the lines of Figures 1 to 6 only in this case the front and back legs are flexibly connected by three spring members. The saddle spring 8 consists of a semi-elliptic spring but the stirrups are supported by two reversed semi-elliptic springs 30 and 31 the upper spring 30 being shackled to the front and back legs 1 and 2 on the same brackets 33 and 34 as is the saddle spring 8 and the spring 31 being shackled to the front and back legs by the brackets 35 and 36.

The action of the toy is similar to the construction described above and is shown in Figures 13 and 14. Application of the weight of the rider to the stirrups 12 pivot the legs 1 and 2 approximately about the points of the brackets 33 and 34 with a consequential forward movement of the front legs and application of the rider's weight to the saddle 8 pivots the legs in the opposite direction with a consequential forward movement of the rear legs.

A body or covering may enclose the framework of the toy to simulate a car, horse or other shape. Apart from the spring members where used, the legs and other members of the framework of the toy may conveniently be constructed out of angle iron, T-section or any other desired section and where possible it is found economical to weld all the joints. The covering may take the form of a flexible material suitably padded and carried on a flexible framework for example a coiled or helical wire framework which may surround the saddle and stirrup supporting members and also, if desired, the legs. Alternatively, the covering may constitute rigid portions, flexibly joined to allow for the action of the apparatus. The wheels on which the toy is mounted may be metal tyred or provided with rubber tyres, solid or pneumatic, and instead of pawl and ratchet mechanism may have any other type of mechanism which will permit them only to rotate in one direction, and the wheels may also, if necessary, be provided with suitable braking mechanism which may be controlled by the rider.

Whilst the invention has been described more particularly with respect to toys suitable for children it may also be constructed for use by adults, for example, in fairground apparatus or, alternatively, for exercise purposes since most of the body and leg muscles are exercised in operating the apparatus of the present invention.

What I claim is:

1. In a wheeled toy including front and back legs supported on wheels adapted to rotate in one direction only, in combination, a saddle support comprising a laterally flexible metal strip connecting the front and back legs, a second flexible connection joining the front and back legs disposed below the saddle support and a stirrup carried by said second connection, said flexible metal strip and said second connection coacting to maintain said legs in spaced apart relation when the toy is not being operated and being so arranged that alternate application of weight on said saddle and said stirrup causes said legs to alternately angle toward and away from one another to produce a progressive movement of the toy.

2. A wheeled toy including front and back legs supported on wheels adapted to rotate only in one direction, a saddle support comprising an upwardly bowed semi-elliptic spring connecting the front and back legs and flexible connecting means joining said front and back legs below said saddle support and a stirrup carried on said flexible connecting means, said semi-elliptic spring and said other flexible connecting means being so arranged that depression of the semi-elliptic spring causes the ends thereof to move apart whereby one of said wheels is moved towards the other and depression of the other flexible connecting means causes said other wheel to move away from said one wheel.

3. A wheeled toy including front and back legs supported on wheels adapted to rotate only in

one direction, a saddle support comprising an upwardly bowed semi-elliptic spring connecting the front and back legs, flexible connecting means joining said front and back legs below said saddle support, a stirrup carried on said flexible connecting means and means for steering the front legs, said semi-elliptic spring and said other flexible connecting means being so arranged that depression of the semi-elliptic spring causes the ends thereof to move apart whereby the front and back wheels are moved towards one another and depression of the other flexible connecting means causes the front and back wheels to separate.

4. A wheeled toy as claimed in claim 2 wherein the flexible connecting means joining said front and back legs below said saddle support comprises a second semi-elliptic spring.

5. A wheeled toy as claimed in claim 2 wherein the flexible connecting means joining said front and back legs below said saddle support comprises a second upwardly bowed semi-elliptic spring and wherein a third but downwardly bowed semi-elliptic spring secured in the middle to the second upwardly bowed semi-elliptic spring connects the front and back legs at points adjacent those at which the saddle support spring connects said legs.

6. A wheeled toy as claimed in claim 2 wherein said flexible connecting means joining the front and back legs below the saddle support comprises a knuckle joint, the arms of said knuckle joint being fixedly connected to the front and back legs, means being provided for limiting the angular movement of the knuckle joint in both directions.

7. A wheeled toy as claimed in claim 2 wherein the flexible connecting means joining said front and back legs below said saddle support comprises a knuckle joint, the arms of said knuckle joint being fixedly connected to the front and back legs, means being provided for limiting the angle movement of the knuckle joint in both directions and wherein the front end of the saddle support spring and the front end of the front arm of the knuckle joint are secured to a bracket which is pivotally connected to the front legs to permit rotation of said legs about a substantially vertical axis to enable said toy to be steered.

8. A wheeled toy as claimed in claim 2 wherein said flexible connecting means joining the front and back legs below the saddle support comprises a knuckle joint, the arms of said knuckle joint being fixedly connected to the front and back legs and wherein L-shaped cleats are secured to the arms of the knuckle joints which cleats engage extensions of the arms beyond the pivot point to limit the angular movement of the knuckle joint in both directions.

9. A wheeled toy as claimed in claim 1 wherein the flexible connection means comprises a U-shaped spring having flat arms the front legs being pivotally connected to the ends of the U-spring and the rear legs being secured to the base of the U-spring the upper arm of said U-spring being adapted to receive a saddle and the lower arms being adapted to receive a stirrup.

10. In a wheeled toy including front and back legs supported on wheels adapted to rotate in one direction only, in combination, a saddle support comprising a laterally flexible metal strip connecting the front and back legs, a second flexible connection joining the front and back legs disposed below the saddle support and a stirrup carried by said second connection, said flexible metal strip and said second connection being so arranged that application of weight on said saddle causes said legs to angle toward one another and application of weight on said stirrup causes said legs to angle away from one another, thereby producing progressive movement of the toy.

11. In a wheeled toy including front and back legs supported on wheels adapted to rotate in one direction only, in combination, a saddle support comprising a laterally flexible metal strip connecting the front and back legs, a second flexible connection joining the front and back legs disposed below the saddle support and a stirrup carried by said second connection, said flexible metal strip and said second connection being so arranged that alternate application of weight on said saddle and said stirrup causes said legs to alternately angle toward and away from one another to produce a progressive movement of the toy, and said second flexible connection being provided with means limiting the flexing movements thereof.
